UNITED STATES PATENT OFFICE.

WILLIAM ILE, OF LITTLE FALLS, NEW JERSEY, ASSIGNOR TO ILEITE ELECTRIC MANUFACTURING CORPORATION, OF TUCKAHOE, NEW YORK, A CORPORATION OF NEW YORK.

THREE-WAY ELECTRIC PLUG.

Application filed March 19, 1925. Serial No. 16,606.

This invention pertains to a multiple socket fixture, wherein the casing comprises moulded electrical insulating material. One of the difficulties arising from the manufacture of fixtures having moulded casings is the liability of the casing to crack particularly in the region adjacent the metallic parts which are embedded within the casing, during the forming operation.

10 The present invention is concerned with the provision of a fixture which obviates the necessity for embedding the contact plate within the insulating material during the forming operation, and which reduces the percentage of breakage during the manufacturing operation.

A preferred object of my invention is the provision of a three way socket wherein the cooperating contact members are positioned 20 within a casing without necessitating the employment of a number of small securing members. An advantage of this invention is the ease with which the cooperating parts may be assembled, and the rigidity of such parts when in use.

The preferred form for carrying out my invention is illustrated in the drawings, wherein Fig. 1 is a plan view of an electric fixture embodying my invention; Fig. 2 is 30 an end elevation of this fixture shown in Fig. 1; Figs. 3 and 4 are sections taken on the lines 3-3 and 4-4 respectively in Fig. 1; Figs. 5 and 6 are perspective views illustrating two forms of contact plates used in the fixture.

My fixture is shown in connection with a casing 10 of electrical insulating material, such as bakelite, which is moulded to the desired shape. As shown, the casing has an 40 opening in the nature of a pocket 11 adjacent the middle portion thereof and has passageways 12 and 13 leading outwardly from the pocket in one direction, with passageways 14 and 15 leading outwardly from the pocket 45 in the opposite direction. Additional passageways 16 and 17 are shown as extending longitudinally of the pockets. These last mentioned passageways however are spaced apart by a wall 18 which is formed integral- 50 ly with the casing. Current may be brought into the fixture through inlet contact plates 19 and 20 which have opposite polarity.

A threaded shell or socket 21 within the pocket 11 is shown as being electrically con-

nected at 22 to the plate or blade 20 and as 55 being electrically insulated from the blade 19. The threaded shell provides a socket into which an electric device such as a lamp may be inserted. The socket also functions to position contact plates 24 and 25 within 60 the passageways 13 and 15 respectively. The blades 24 and 25 therefore have the same polarity as the socket 21.

The blade 19 is electrically connected to a blade 26 which preferably embodies a one 65 piece member and extends into the passageways 12 and 14 respectively. The blade 26 therefore has a polarity opposite to that of the blades 24 and 25, and cooperates therewith to provide an outlet on each end of the 70 casing.

A threaded member 28 is shown in Figs. 3 and 4 as being employed for positioning the blades 19 and 26 as well as the socket 21 within the casing. Suitable electrical insulating members 29 and 30 may be employed for preventing a short circuit between the blade 19 and the socket. 75

The construction thus described provides an electric fixture wherein the casing may be 80 moulded without requiring any of the metallic parts to be embedded therein. This reduces the percentage of breakage during the manufacturing operation. A further advantage of the device embodying my invention 85 is the fact that only one threaded securing member need be employed for positioning the various parts within the casing. This facilitates the assembly of the device, and reduces the tendency for breakage during 90 use.

Having thus described my invention, I claim:

1. In a device of the character described, the combination with a casing of electrical 95 insulating material having a pocket therein, and having a pair of passageways leading outwardly from the pocket in opposite directions, a contact plate extending across the pocket and into one of the passageways 100 on each side of the pocket, a threaded socket member mounted in the pocket and opening outwardly, a separate contact plate in each of the remaining passageways, said separate plates cooperating with the first mentioned 105 plate to provide independent outlets and having a portion thereof in abutting engagement with the socket member to provide

- electrical contact therewith, inlet current 55
conducting members longitudinally of the
pocket, means for electrically connecting
one of the members to the socket member,
means for electrically connecting the other
member to the first mentioned contact plate.
2. In a device of the character described,
the combination with a casing having a cen-
trally located pocket and having a pair of
passageways leading outwardly from the
pocket in opposite directions, a contact blade
common to two of the passageways, a single
socket member in the pocket, independent
contact blades in the remaining passage-
ways, each of the independent blades hav-
ing a laterally extending portion engaging
the socket member and providing an elec-
trical contact therewith, a pair of current
carrying members disposed within the cas-
ing and projecting outwardly therefrom,
one of said members being electrically con-
nected to the socket member, the other of
said members being connected to the first
mentioned contact plate, and means for
holding said socket member and blades with-
in the casing. 70
3. In a device of the character described,
the combination with a casing having a cen-
trally located pocket and having a pair of
passageways leading outwardly from the
pocket in opposite directions, a contact blade
common to two of the passageways, a threaded
socket member in the pocket, inde-
pendent contact blades in the remaining pas-
sageways, each of the independent blades
having a laterally extending portion en-
gaging the outer surface of the socket mem-
ber and providing an electrical contact
therewith, a pair of current carrying mem-
bers disposed within the casing opposite the
socket and projecting outwardly therefrom
parallel with the axis of the socket, one of
said members being electrically connected to
the socket member, the other of said mem-
bers being connected to the first mentioned
contact plate, and a screw located at the
axis of the socket and connected to the last
mentioned inlet member and insulated from
the socket member and serving to position
said socket member and blades with refer-
ence to the casing. 90
4. In a device of the character described,
the combination of an electrical insulating
casing having a pocket in one side, a
threaded sleeve in the pocket, a pair of inlet
contact members extending into the opposite
side of the casing, one of said members
joined to said sleeve and the other of said
members being connected to a central con-
tact member comprising a screw at the axis
of the sleeve, and two pairs of contacts each
pair on opposite sides of the sleeve, each of
said contacts being located within an ex-
posed recess in the casing, and one of the
contacts of each pair abutting the side of
the threaded sleeve, and the other contact
of each pair and extending across the base
of the sleeve and insulated from it and be-
ing connected by the central screw with one
of the inlet members. 100
5. In a device of the character described,
the combination with a casing of electrical
insulating material having a pocket therein,
and having passageways leading outwardly
in pairs directly from the pocket, the inner
passageway of each pair entering the pocket
adjacent its base and the outer passageway
of each pair abutting the side of the pocket,
a threaded socket member within the pocket,
contact plates within the outer passageways
and in abutting engagement with the outer
surfaces of said contact member, conducting
blades in other passageways, a second con-
tact plate of opposite polarity to the first
mentioned plates in the inner passageways
and extending across said pocket and being
electrically insulated from the socket mem-
ber, and a single securing member for posi-
tioning the socket member and said blades
within said casing. 85
6. In a device of the character described,
the combination of an insulating body hav-
ing a cylindrical pocket and two aligned di-
ametrically opposite cylindrical extensions
on an axis transverse of the pocket, each ex-
tension having two passageways one abutting
the side of the pocket and the other register-
ing with the base of the pocket, a metallic
threaded shell in said pocket, separate con-
tact strips in the passageways opposite the
sides of the pocket, which strips contact
with the shell, a strip in the passageway
registering with the base of the pocket in-
sulated from the shell, and the central con-
tact connected with the last mentioned strip. 95
- In testimony whereof, I hereunto affix my
signature.

WILLIAM ILE.
